UNITED STATES PATENT OFFICE.

EDWARD W. ANDEREGG, OF ALGOMA, WISCONSIN, ASSIGNOR TO THE ALGOMA FLY NET COMPANY, OF ALGOMA, WISCONSIN, A CORPORATION OF WISCONSIN.

NET.

1,150,325.

Specification of Letters Patent. Patented Aug. 17, 1915.

Application filed November 12, 1914. Serial No. 871,734.

To all whom it may concern:

Be it known that I, EDWARD W. ANDEREGG, a citizen of the United States, residing at Algoma, in the county of Kewaunee and

5 State of Wisconsin, have invented certain new and useful Improvements in Nets, of which the following is a specification, reference being had to the accompanying drawings.

10 This invention relates to certain improvements in nets and has relation more particularly to a device of this general character especially designed and adapted for use as a fly net for animals; and the object of the 15 invention is to provide a novel and improved device of this character whereby the cords are effectively maintained in their predetermined spaced relation and effectively engaged with the fabric bars.

20 The invention consists in the details of construction and in the combination and arrangement of the several parts of my improved net whereby certain important advantages are attained and the device is rendered simpler, less expensive and otherwise 25 more convenient and advantageous for use, all as will be hereinafter more fully set forth.

The novel features of the invention will 30 be carefully defined in the appended claims.

35 In order that my invention may be the better understood, I will now proceed to describe the same with reference to the accompanying drawings, wherein—

Figure 1 is a fragmentary view in top plan of a net constructed in accordance with an embodiment of my invention, one of the flexible bars therein included being omitted in order to illustrate in detail certain features of the invention; and Fig. 2 is a fragmentary view in plan of the net as herein embodied, with a ply of a flexible bar removed.

As disclosed in the accompanying drawings, 45 1 denotes the conventional strands or cords adapted to be disposed between the plies 2 of the flexible bars B, said plies being operatively connected one with the other through the medium of the rows 3 of stitch-

ing, and which rows of stitching are also adapted to maintain the strands in predetermined spaced relation. 50

In order to assure the proper spacing of the strands 1, I find it of advantage to employ in connection therewith the tie members 4, herein disclosed as consisting of 55 strands of wire of predetermined gage twisted one about the other and with which the strands 1 intermesh. In practice, it is my purpose to have a tie member 4 interposed between the plies 2 of each of the 60 flexible bars B, said bars B being of a number which best meets the requirements of practice.

It will be observed that the tie members 4 possess sufficient rigidity as to positively 65 maintain the strands in their predetermined spaced relation and it will also be readily perceived that the tie members 4 prevent the strands or cords 1 from slipping longitudinally between the plies 2 of the bar B, 70 especially in such instances when the stitching fails to catch a cord or strand.

From the foregoing description, it is thought to be obvious that a net constructed in accordance with my invention is of an 75 extremely simple and comparatively inexpensive nature and is particularly well adapted for use by reason of the convenience and facility with which it may be assembled, and it will also be obvious that my invention is susceptible of some change and modification without material departure 80 from the principles and spirit thereof and for this reason I do not wish to be understood as limiting myself to the precise arrangement and formation of the several parts herein shown in carrying out my invention in practice. 85

I claim:

1. A net comprising a flexible bar consisting of superimposed plies, cords directed between the plies of the bar, and a substantially rigid member engaged with the cords and positioned between the plies of the bar and serving as a means to maintain the 95 cords in predetermined spaced relation, said

rigid member consisting of strands of wire twisted one about the other and with which the cords intermesh.

2. A net comprising a plurality of cords, 5 and a substantially rigid member engaged with the cords and serving as a means to maintain the cords in predetermined spaced relation, said rigid member consisting of

strands of wire twisted one about the other and with which the cords intermesh.

10

In testimony whereof I hereunto affix my signature in the presence of two witnesses.

EDWARD W. ANDEREGG.

Witnesses:

Wm. E. PERRY,
JERRY JAUBET.
